UNITED STATES PATENT OFFICE.

STEPHEN KEINER, OF LOS ANGELES, CALIFORNIA.

GAME APPLIANCE.

Application filed November 6, 1922. Serial No. 599,388.

To all whom it may concern:

Be it known that I, STEPHEN KEINER, a citizen of Austria-Hungary Slavonia, having declared my intentions of becoming a 5 citizen of the United States, residing at Los Angeles, in the county of Los Angeles and State of California, have invented a new and useful Game Appliance, of which the following is a specification.

10 This invention relates to an educational game adapted principally to kindergarten use of teaching young children the rudiments of mathematics, and at the same time interesting and entertaining them.

15 An object of the invention is to provide a simple, cheap and harmless appliance for use in interesting and educating children. To that end I provide an appliance on which a game can be played that is interesting and 20 educational to children; and constructed so that a game can be played thereon without the least danger of being injurious to the players. In kindergarten schools it is especially desirous to have harmless 25 appliances that the very young children can handle successfully without hurting themselves; and, in addition to interesting them as a mere game to also familiarize them with the rudiments of numbers.

30 An object of the invention is to provide an appliance on which a game can be played with results of great uncertainty. That is, a play can be made with a credit of zero; or a possible credit of forty-five or more.

35 An object of the invention is to provide an appliance on which a game can be played that will interest a large number of players. That is, an entire kindergarten class can participate in each play by each of them 40 computing the results of the play.

A feature of the invention is shown in the over-balanced runway that is actuated into a horizontal plane by the impact of a ball, the force of which causes the over-balanced 45 runway to rebound and discharge or catapult the ball toward the front of the appliance; and in this respect the invention is broadly new, basic and pioneer.

A feature of invention is shown in the 50 construction, combination and arrangement of the various parts; whereby the uprights and runways are collapsible so that the parts can be flattened out into a small space for shipping or storing.

55 Other objects, advantages and features of invention may appear from the accompany-

ing drawing, the subjoined detail description and the appended claims.

The accompanying drawing illustrates the 60 invention.

Figure 1 is a plan view of the appliance with the balls arranged in position to play.

Fig. 1^a is a side elevation of the appliance on a reduced scale showing the runways collapsed and arranged for packing. 65

Fig. 2 is a longitudinal section on line x², Fig. 1; also showing by dotted lines an altered position of the over-balanced runway; also indicating by dotted lines the parts in collapsed position. 70

Fig. 3 is a rear end view of the appliance.

Fig. 4 is an enlarged fragmental sectional view of the lower rear end position of Fig. 2; showing by full line the over-balanced runway moved from its normal inclined, 75 position that is indicated by dotted lines.

Fig. 5 is an enlarged cross-section on line x⁵, Figs. 1 and 2.

Fig. 6 is an enlarged cross-section on line x⁶, Figs. 1 and 2. 80

Fig. 7 is an enlarged fragmental view of the lower right hand corner portion of Figs. 2, 4 showing the runway saddle in detail.

Fig. 8 is an enlarged cross-section on line x⁸, Fig. 2. 85

Fig. 9 is a diagrammatic grouped view of the player balls; showing them in preferred colors.

The game appliance consists of a base 1 provided with a large forward end in the 90 center of which is arranged a field a on which is placed the field balls b, c.

The base 1 is provided with the enclosure wall 2 that extends entirely around the front and sides of the base; and the wall 95 is of a sufficient height to prevent the field balls b, c, and the player balls d from escaping from the upper surface of the base 1 when they are in action.

At the rear of base 1 is an end plate 3 that 100 extends upward a considerable height; and this plate abuts the rear ends of walls 2 to form a complete enclosure around the base 1; and it is attached by hinges 3' thereto so that it can be folded down toward the 105 base 1.

At opposite sides of base 1 and near the center thereof are the uprights 4 to which is secured a cross plate 5. The top end of plate 3 is reduced in width and has a recess 6 adjacent to which is fitted the rear ends 110 of the planks 7, 8 of the upper runway and

these planks are attached by hinges 7' to the end 3 so that the runway can also be folded down; and also these planks extend over and normally rest onto the cross plate 5; and preferably the uprights 4 are of sufficient length to support the planks 7, 8 in an elevated and inclined position, with their forward ends much higher than the rear ones; and planks 7, 8 are spaced apart to 10 form an elongated ball seat 9' between them. The bottom ends of uprights 4 are secured to the walls 2 by screws 4' one of which is removable when the uprights are to be folded down as shown in Figs. 1^a, 2.

15 The forward end of the upper runway 9 has a ball starting enclosure 10 into which the balls are placed when they are to be played.

20 There is a rectangular opening 11 cut through the end plate 3 and through this opening is extended the heavy end portion 12 of the over-balanced runway 13. The end portion 14 of this balance extends outward from end plate 3 and normally upward; and there is an enclosing wall 15 extending across the end and sides of end portion 14.

25 On the underside of the runway 13 is a saddle 16 comprising a pivotal surface 17 on the underside of the runway; and on opposite sides of this pivotal surface are contact blocks 18, 19.

30 The block 18 has a surface 20 that normally engages the inner surface of wall 3; 35 that is moved out of contact with wall 3 when the runway is actuated by the impact of a player ball that falls from the upper runway 9 onto the end portion 14 of lower runway 13.

35 The block 19 is secured to the bottom of runway 13 so that normally there is a clearance between its inner surface 21 and wall 3; and so that this block is moved into engagement with the wall when the runway is actuated from its inclined position to a substantially horizontal position.

40 The runway 13 is pivotally mounted on the ledge 22 of wall 3 so that when a player ball falling from the discharge end of the upper runway 9 and strikes and forces the end 14 downward the runway 13 will be moved to a horizontal position; and move block 19 into impacting engagement with the wall 3; and the impacting contact of block 19 with wall 3 causes a rebound of the runway to normal position; and also causes the player ball to rebound toward the front end of the appliance.

45 The runway 13 is constructed so that it can be lifted out of the opening 11 in end 3 and placed in a flat position over the folded upper runway as indicated in Figs. 1^a and 2.

50 The field balls *c* are arranged in the field *a* in the form of a hollow square that lays at a 65 ninety degree angle to the longitudinal axis

of the base; and in the center of this square is the ball *b* and preferably ball seats 23 are formed by slight recesses in the top surface of base 1 so that the field balls are not easily displaced by a player ball; and also so they can be easily replaced when knocked out of position.

60 At the forward end of the base 1 there is a rectangular depression 24 that is divided in a number of compartments 25 that are adapted to receive either the player or field balls; and these compartments are numbered from 1 to 9 with the numbers arranged with 9 at the center and the other numbers 8, 6, 4, 2 and 7, 5, 3, 1 at opposite sides of it, see Fig. 2.

65 Also indicated by dotted lines are a number of small counterfields on the face of the base that are arranged adjacent the ball field *a* into which both the player and field ball can enter when a play is made; and these fields are numbered from 1 to 12 so that a ball knocked from field *a* into any one of the surrounding fields or onto any of the compartments in depression 24 have a counting value. Also if desired any of the player balls entering these fields can have a counter value.

70 Preferably the player balls are colored red, white and blue as diagrammatically illustrated in Fig. 9, and also they are slightly larger than any of the field balls.

75 The field balls can be of any desired color that will readily distinguish them from the player balls; and the center ball *b* is larger than the surrounding balls *c*.

80 Various counting games can be played; and for the sake of brevity only one will be given.

85 The player balls in this game are played in the order of red, white and blue; and these balls are consecutively placed in the enclosure 10 and released to roll by gravity down the runway 9 and fall onto the tilting runway 13 where as previously described the 90 balls are catapulted toward the balls in field *a* with considerable force; and the field balls are arranged so that a strike can be made; or so that all of the field balls can be displaced by a single play; a strike however, 95 is rarely made.

100 In this game it is preferable that the ball *b* has a double counter value, and the balls *c* each a single counter value. That is if ball *b* is displaced from field *a* and passes 105 into any of the numbered spaces or fields the number is doubled. That is if ball *b* rolls into space 2 it would count 4, in space 3, its value would be 6 and so on. The other field balls *c* have the counting value into whichever space they pass; that is, if a ball *c* rolls into space 2 it counts 2 and if in the 110 3, 4 or any other number that is its numerical value.

115 Preferably the red ball is played first for 120

addition and it and also all the balls in field *a* that are displaced and roll into a counter square are added together to make a first sum. Assuming that this ball is played 5 and it knocks four of the balls *c* into the respective spaces of 2, 4, 6, 8, and the ball *b* into the space 9, the first sum would be 38; or the product 2 plus 4 plus 6 plus 8 plus twice 9.

10 The white ball represents subtraction and it is played to displace any of the remaining balls on field *a* and the numerical subtracting value of this play depends on the number of balls displaced and the spaces 15 into which they rest. Assuming that three of the remaining balls *c* together with the white ball enter the respective spaces 1, 3, 5, 7 the sum of these numbers is subtracted from the total 38 or 22.

20 Then the blue ball is played which represents multiplication. Now assuming that it displaces the remaining ball *c* and the balls pass into the respective spaces of 1 and 4 making a sum of 5 with which to multiply 22 25 making a total of 110, for the play. Division is accomplished in the game by dividing the total acquired by addition, subtraction and multiplication by the number of balls remaining on the field 2.

30 Assuming that the three player balls have been played acquiring a total of 110 with two of the field balls remaining in the square *a*, then the sum of 110 is divided by 2 making a final total of 55.

35 From the foregoing it can readily be seen that quite a number of games can be devised that are exciting and interesting to children which when played enables them to unconsciously and easily acquire the rudiments of 40 mathematics.

I claim:

1. A game appliance comprising a base; an enclosure for the front and sides of said base; an upright plate pivotally connected 45 to the rear end of said base; a runway for balls said runway having its rear end pivotally connected to the upper end of said plate; and a folding support for the forward end of said runway.

2. A game appliance comprising a base; 50 an enclosure for the front and sides of said base; an upright plate pivotally connected to the rear end of said base; an upper runway for balls said runway having its rear end pivotally connected to the upper end of 55 said plate; a collapsible support for the forward end of said upper runway; and a removable tilting runway for balls below said upper runway.

3. A game appliance comprising a base; 60 an enclosure for the front and sides of said base; an upright plate pivotally connected to the rear end of said base; said upright plate having an opening therethrough; a runway for balls said runway having its 65 rear end hinged to the upper end of said plate; a support for the forward end of said upper runway said support adapted to be folded toward said base; and an overbalanced 70 runway for balls extending partly through the opening through said plate, said overbalanced runway arranged so that balls falling thereon will rebound toward the forward end of said base.

4. A game appliance comprising a base 75 having a top surface and a rear and front end; an enclosure for the sides and front end of said base; a depression at the forward end of said base said depression having a number of numerically indicated compartments; 80 a field arranged at the forward end of said base; field balls arranged in a hollow square on said field with a double value ball in the center of the square; counter fields arranged adjacent the ball field; player balls; 85 an inclined upper runway over which the player balls can pass from the front toward the rear of said runway; means whereby the player balls falling from the rear end of said upper runway will rebound toward the field balls to displace them and drive said field balls toward the counter fields. 90

In testimony whereof, I have hereunto set my hand at Los Angeles, California, this 28th day of October, 1922.

STEPHEN KEINER.
